(57) **CLAIM**

We claim the ornamental design for a reticle for rangefinder, as shown and described.

DESCRIPTION

FIG. 1 is a front view of our new design for a reticle for rangefinder according to a first embodiment;

FIG. 2 is a top right isometric view thereof shown in a use configuration with environment;

FIG. 3 is a front view of our new design for a reticle for rangefinder according to a second embodiment; and,

FIG. 4 is a top right isometric view thereof shown in a use configuration with environment.

Evenly broken lines in FIGS. 1-4 are for environmental purposes and form no part of the claimed design.

Unevenly broken lines in FIGS. 1-4 indicate a boundary of the claimed design.
